<img alt="A detailed technical line drawing of a mechanical assembly, labeled 'Fig. 4.' at the top. The drawing shows a top plate 80 with a central slot 82. A central vertical assembly 144 is mounted on the plate. This assembly includes a base 112, a central vertical member 118, and a top cap 114. A horizontal member 100 is attached to the top cap 114. A flexible hose 96 is attached to the top cap 114 and passes through the slot 82. A support structure 92 is attached to the side of the central vertical member 118. The base 112 is supported by a threaded bolt 104, which is secured to a flange 98. The flange 98 is bolted to a base plate 102. Various other components are labeled with numbers such as 10, 16, 32, 44, 50, 54, 56, 76, 102, 112, 118, 120, 122, 124, 144, 146, 148, 150, 152, 154, 156, 158, 160, 162, 164, 166, 168, 170, 172, 174, 176, 178, 180, 182, 184, 186, 188, 190, 192, 194, 196, 198, 200, 202, 204, 206, 208, 210, 212, 214, 216, 218, 220, 222, 224, 226, 228, 230, 232, 234, 236, 238, 240, 242, 244, 246, 248, 250, 252, 254, 256, 258, 260, 262, 264, 266, 268, 270, 272, 274, 276, 278, 280, 282, 284, 286, 288, 290, 292, 294, 296, 298, 300, 302, 304, 306, 308, 310, 312, 314, 316, 318, 320, 322, 324, 326, 328, 330, 332, 334, 336, 338, 340, 342, 344, 346, 348, 350, 352, 354, 356, 358, 360, 362, 364, 366, 368, 370, 372, 374, 376, 378, 380, 382, 384, 386, 388, 390, 392, 394, 396, 398, 400, 402, 404, 406, 408, 410, 412, 414, 416, 418, 420, 422, 424, 426, 428, 430, 432, 434, 436, 438, 440, 442, 444, 446, 448, 450, 452, 454, 456, 458, 460, 462, 464, 466, 468, 470, 472, 474, 476, 478, 480, 482, 484, 486, 488, 490, 492, 494, UNITED STATES PATENT OFFICE.

FRANS EDWARD FORSELL, OF PROVIDENCE, RHODE ISLAND, ASSIGNOR TO PARKS BROS. & ROGERS, INC., OF PROVIDENCE, RHODE ISLAND, A CORPORATION OF RHODE ISLAND.

SEPARABLE BUTTON.

Application filed February 4, 1925. Serial No. 6,367.

To all whom it may concern:

Be it known that I, FRANS EDWARD FORSELL, a citizen of the United States, residing at Providence, of the county of Providence and State of Rhode Island, have invented certain new and useful Improvements in Separable Buttons, of which the following is a specification.

My invention relates to separable cuff buttons. The main object of my invention is to provide a cuff button, the parts of which will become securely locked together on relative tilting thereof. So far as I am aware no one has hitherto provided a separable cuff button which will securely lock on relative tilting movement of the component members thereof alone.

To this end I provide a separable cuff button preferably comprising two co-operating male and female members each having a head, a shank and a base, the head of the male member comprising a cup-shaped guiding flange projecting integrally arcuately outwardly and upwardly from the shank, the upper portion thereof being bent back on itself over the lower layer thereof to form a strengthening radially inwardly projecting flange terminating in a central hole, the upper surface thereof forming a concave guiding surface and a stud member having a stem mounted centrally of said shank and a mushroom shape head having a flat upper surface provided with a central annular ridge and a convex lower surface offset from said concave guiding surface, the shank of the female member terminating in an arcuately radially spread out flange the lower portion thereof being bent back on itself over the upper layer to form a strengthening radially inwardly projecting flange terminating in a central hole, and having an annular washer provided with a central hole resting on the lower portion of said flange a cap over said radial shank

flange the lower surface of the wall thereof forming a convex surface to co-operate with the concave guiding flange of the male member, the lower portion of said wall terminating in a central circular hole of slightly greater diameter than the head of the stud of the male member to form a substantially spherical socket having an annular arcuate lip adapted to register in a portion of the annular space formed between the guiding

flange and head of the stud of the male member to retain said members together when relatively tilted off centre in use, a washer centrally mounted in the base of the female member having a central hole, a spiral spring having the base thereof resting within said hole and a stud member slidably mounted in the shank thereof having the base thereof resting on the top of the spiral spring and the head thereof projecting into said socket having a shoulder adapted to abut the edges of the hole in said washer to limit its downward movement and a pointed head adapted to resiliently spring within said annular ridge on the head of male member to centre said members on relative tilting thereof to permit withdrawal of the lip of the female member over the head of the stud of the male member. In this description I refer to the parts of the button in the position they take in use with the female member uppermost.

It is obvious that my invention will function without the spring, without the resiliently slidably mounted member and that on mere tilting of said members the lip of the female member will move into the annular space between the convex guiding flange and head of the stud of the male member to securely interlock said members. When in this position it is obvious that it is impossible to separate said members with a straight pull. A further object of my invention is therefore to provide a separable cuff button which when locked becomes impossible to separate during normal use thereof.

As stated, when the resiliently slidably mounted member is employed, the heads or cooperating complementary latch portions of said members will become coupled and the members will be securely interlocked at an angle to one another after said portions are brought into contact with each other and said members are manually tilted in any direction. Where the resiliently slidably mounted member is omitted however, the cooperating complementary latch portions will become merely coupled, and said members will not be securely interlocked at an angle to each other after said portions are brought into contact with each other and said members are manually tilted, but will be free to pivot on each other, although

while coupled, it is obvious that it will be impossible to separate said members on a straight axial pull of each member.

A further object of my invention is to provide a cuff button which through all possible universal movements thereof will conform to the angularity of the cuff whether a soft cuff or a stiff cuff be employed.

A further object of my invention is to provide a separable cuff button which can be inserted and locked in any way or in any position in day-light or darkness.

As described above, I slidably resiliently mount a stud having an end projecting into the socket of the female member and I provide a cooperating annular ridge on the upper surface of the head of the male member. These cooperating features perform several functions. When the members are relatively tilted to locked position, it is obvious that the end of the stud will be resiliently pushed exterior of the ridge in the stud of the male member. To centre said members to unlock, it is therefore necessary to exert sufficient force to push the end of the slideable stud in the female member over the ridge in the stud of the male member against the pressure of the spring. The slideable stud therefore serves as a means to keep the stud in locked position. When it is desired to separate the members, the bases of said members are grasped between the fingers and sufficient force is exerted to axially align said members, the end of the stud being pushed against the pressure of the spring over the ridge in the head of the male member into the cup shaped depression formed therein between the edges of said ridge. The ridge being of a sufficient size to just receive the head of the slideable stud to accurately axially align said members. It is obvious that when in this position the spring will push the stud downward to tend to separate said members. As the central hole of the socket of the female member is of a slightly larger diameter than the diameter of the head of the stud of the male member it is obvious that the edges of the head of the stud of the male member may slide past the edges of the lip of the female member thus permitting separation of said members the spring actually assisting therein.

Further objects of my invention therefore are to provide a separable cuff link which can be readily unlocked by mere axial alignment of said members.

A further object of my invention is to provide a construction which will function without any protruding parts or levers to catch or tear the cuffs.

A further object of my invention is to provide a construction wherein the stem of the male member comprises a flat head and not a long projecting stem as in former

types which makes insertion of the male member into the cuff a difficult operation.

A further object of my invention is to provide a workable structure having no projecting knobs or parts on the base of said members so as not to interfere in any way with the placing of the usual desirable designs thereon and thus to provide a very neat finished article.

A further object of my invention is to provide a separable cuff button which can be locked and unlocked by mere grasping of the bases thereof between the fingers without the necessity of inserting the fingers between the cuffs to soil or dirty them.

These and such other objects of my invention as may hereinafter appear will be best understood from a description of an embodiment thereof such as shown in the accompanying drawings.

In the drawings, Fig. 1 is a side elevation of a separable cuff button made in accordance with my invention in locked position, the position of the cuffs being shown in dotted lines.

Fig. 2 is a cross sectional view of my invention in locked position.

Fig. 3 is a cross sectional view of my invention with the male and female members axially aligned to permit separation thereof.

Fig. 4 is a cross sectional view similar to Fig. 3 after the spring has functioned to just withdraw the lip of the socket of the female member over the edge of the stud of the male member.

Fig. 5 is a side elevation of my invention showing the male and female members in the position they assume when separation is completed, the position of the cuffs being shown in dotted lines.

Fig. 6 is a plan view of the male member of my invention.

Fig. 7 is a plan view of the female member of my invention.

Fig. 8 is a detailed perspective view of the disassembled parts of the male member of my invention arranged in assembled sequence.

Fig. 9 is a detailed perspective view of the disassembled parts of the female member of my invention arranged in assembled sequence.

In the drawings, wherein like characters of reference indicate like parts throughout, 10 generally indicates a cuff button made in accordance with my invention. 12 generally indicates the male member of my invention and 14 the female member thereof. The respective male and female members 12 and 14 each having the heads 16 and 18 respectively, the shanks 20 and 22 respectively and the bases 24 and 26 respectively. The bases 24 and 26 may be ornamented if desired in any suitable fashion. When in at-

tached position the button holes 28 of the cuffs 30 normally surround the respective shanks 20 and 22 of said members. The heads 16 and 18 of said members comprise 5 the cooperating male and female portions adapted to securely interlock said members when said members are relatively tilted or oscillated off centre in use. The head 16 of the male member comprises a cup shaped 10 guiding flange 32 projecting integrally arcuately outwardly and upwardly from the shank 20 thereof, the upper portion 34 thereof being bent over on itself over the lower layer 35 thereof to form a strengthening 15 radially inwardly projecting flange 34 terminating in a central hole 36, the upper surface 38 thereof forming a concave guiding surface and a stud member 40 having a stem 42 mounted centrally of the shank 20 20 and a mushroom shaped head 44 having a flat upper surface 46 provided with a central annular ridge 48 enclosing the cup-shaped depression 50 and a convex lower surface 52 offset from said concave guiding 25 surface. As seen in Fig. 8, I provide the circular washer 54 adapted to be inserted in the base 24. The shank 20 is provided with the radially projecting flange 56 which is adapted to be seated within the base 24 over 30 the washer 54 and to be secured thereto by having the lips or upstanding sides 58 of the base 24 crimped over as at 60 to secure the flange 56 of the shank 20 to the base 24. To provide a shank head of greater 35 strength, I preferably construct the shank and integral head of the male member by a series of operations performed on blanks as illustrated in our former Patent #1,188,211. The shank shown in Fig. 8 therein being given one further operation to bend down the upper layer 34 in close proximity to the lower layer 35 as heretofore described, thus providing a shank having an outer 40 end of double thickness of metal readily constructed according to the improved process of manufacturing on screw machines. The stem 42 of the stud member 40 is then inserted through the hole 36 in the head of the male member in the hollow shank 20. 45 The lower portion of the stem of the stud member 40 may be channelled as at 61. Though any means may be provided to secure the stem 42 within the shank 20, I preferably fill up the hollow shank with solder 50 62 filling in the channels 61 in the base of the stem 42 of the stud member 40 and filling in the space 64 between the two layers of metal 34 and 35 in the head. The shank 22 of the female member is 55 constructed with the base flange 70 identical in construction to the base flange 56 of the male member and the lower end thereof terminates in an arcuately radially spread out flange 72, the lower portion 74 being 60 bent back on itself over the upper layer 76 to form a strengthening radially inwardly 65 projecting flange 74 terminating in a central hole 78. The shank 22 is thus also constructed in accordance with the method outlined in Patent #1,188,211 and the additional operation just described. I preferably form a circumferential groove 79 on the outer upper surface of the upper layer 76 for a purpose to be described. I provide the base 26 of the female member identical in 70 construction to the base of the male member just described and I insert therein the annular washer 80 provided with the central hole 82 and in said central hole I insert the base 84 of the spiral spring 86, the hole 85 82 in the washer being provided to centre said spring. The base flange 70 is then inserted within the base 26 over the spiral spring 86 and washer 80, and the upper ends of the sides 88 of the base 26 are then crimped over as at 90 to firmly secure the shank 22, washer 80 and spring 86 therein. I then mount the slideable stud member 92 within the hollow shank 22, the base 94 thereof resting against the top 96 of the slideable spring 86. The stud member 92 is of a general cylindrical shape but near its outer end is made of a smaller diameter to provide the shoulder 98 for a purpose to be described and has its outer end preferably 95 tapered to the point 100. I then insert the washer 102 provided with the central hole 104 of a diameter slightly greater than that of the lower end of the slideable stud 92 over the lower layer 74 of the flange 72 of the shank 22. I secure said washer 102 within the shank 22 by the dome shaped cap 106 which has the functions later to be described. The upper edge of the side of the dome shaped cap is provided with the straight edge 108 adapted to be crimped over the circumferential groove 79 in the upper layer 76 of the radial shank flange 72 thus permitting the edges of the washer 102 to rest in the seat 110 provided therefor 110 in the dome shaped cap and firmly secure all parts of said members of the female member together in assembled position. The lower surface of the wall 112 of said cap forms a convex surface 114 adapted to co-operate with the concave guiding surface 38 of the head of the male member. The lower portion of said wall terminates in a central circular hole 116 of slightly greater diameter 115 than the head 44 of the stud 40 of the male member to form a substantially semi-spherical socket 118 having an annular arcuate lip 120. The female member when assembled thus comprises the base 26 having the shank 22 terminating in a radially 120 spread out flange 72, the lower portion 74 thereof being bent back on itself over the upper layer 76 to form a strengthening inwardly projecting flange terminating in the central hole 78, an annular washer 102 pro- 125 130

vided with a central hole 104 resting on the lower surface 74 of said flange, a dome shaped cap 106 secured over said washer 102 to said radial shank flange 72, the lower 5 surface of the wall 112 thereof forming a convex surface 114 to cooperate with the concave guiding surface 38 of the male member and the lower portion of the wall 112 terminating in a central circular hole 116 of slightly greater diameter than the head 44 of the stud 40 of the male member 10 to form a substantially semi-spherical socket 118 having an annular arcuate lip 120 adapted to register in a portion of the 15 annular space 122 formed by the guiding flange 32 and head 44 of the stud of the male member to retain said male and female members together when relatively tilted off centre in use, a washer 80 centrally mounted 20 in the base thereof having a central hole 82 to centre the base 84 of the spiral spring 86 therein and the stud member 92 slidably mounted in the hollow shank 22 thereof having the base 94 resting on the top 96 of the 25 spiral spring 86 and the head 100 thereof projecting into said socket 118 having the shoulder 98 adapted to abut the edges of the hole 104 in the washer 102 to limit the downward movement thereof and a pointed 30 head 100 adapted to resiliently spring within the cup 50 contained within the annular ridge 48 on the head 44 of the male member to axially align said male and female members 14 on relative tilting thereof to 35 permit withdrawal of the lip 120 of the female member 14 over the head 44 of the stud 40 of the male member to permit separation of said members.

Though I have described in detail the 40 preferred embodiment of my invention and illustrated in detail how it may be readily constructed on a screw or other type of automatic machine, it is obvious that other means of assembling, of connecting the 45 various members may be employed, and that any suitable type of spring means to actuate the stud 92 may be employed. My invention broadly comprises as explained a separable cuff button having cooperating 50 male and female portions adapted to securely inter-lock after said portions are brought into contact with each other and said members are manually tilted and if also desired means on said members to relatively axially align said members to permit and assist in separation thereof.

Though I have shown the cooperating male and female members of my invention as the connecting members of a separable 60 cuff button, it is obvious that they may be used as the connecting members of any type of separable fastener without departing from the spirit of my invention.

The operation of my invention is obvious 65 from the above description. Figs. 1-5 show

a separable button employing my invention in the act of being separated. The bases 24 and 26 may be conveniently grasped by the fingers exterior of the cuff 28 and the members 12 and 14 axially aligned as shown 70 in Fig. 3. As heretofore explained the point 100 of the slidable stud member 92 projecting exterior of the ridge 48 when in locked position serves with the resilient pressure of the spring 86 to keep said members in 75 locked position, it being necessary in the operation of axially aligning said members just explained to push the end 100 of the slidable stud member 92 over the ridge 48 of the stud 40 of the male member against 80 the pressure of the type of spring means employed. When the point 100 has slid over the ridge 48 the pressure of the spring 86 will immediately force the point 100 within the cup 50 to axially align said members, as shown in Fig. 3. The spring 86 still functioning will serve to push the stud 92 downwards in the hollow shank 22, the pressure of the spring 86 thus raising up 85 the lip 120 of the socket 118 of the female member over the edge of the stud of the male member until the shoulder 98 abuts the edge of the hole 104 in the washer 102 limiting the downward movement of the stud. The parts at this juncture will assume the position shown in Fig. 4, the end 100 of the stud still registering within the cup 50 in the head 44 of the stud 40 of the male member. The male and female members may then be readily pushed apart to 90 the completely unlocked position shown in Fig. 5.

To lock it is obvious that mere reversal of these operations is necessary. The members 12 and 14 are brought into position with the male portion adjacent to the female portion thereof and may be pressed axially by the fingers as shown in Fig. 5 through the position in Fig. 4 to the position shown in Fig. 3, the end 100 of the stud 92 registering within the cup 50, and the stud 92 being pushed up against the pressure of the spring 86 within the shank 22 until the convex surface 114 of the female member 14 engages the complementary concave guiding surface of the male member 12. When the parts are in this position on relative tilting movement, the end 100 of the stud 92 is drawn out of the socket 50 over the ridge 48, the cooperating concave and convex surfaces 38 and 114 sliding over each other in any direction and the lip 120 registering in the annular space 122 formed between the convex lower edge 52 of the stud 44 and the concave guiding surface 38 of the flange 32. After the end 100 of the slidable stud 92 has passed over the annular ridge 48 the spring 86 will force the end 100 down again as shown in Fig. 2 to assist in retaining said members in position off centre, the head 44 100

105

110

115

120

125

130

of the stud 40 overlapping the lip 120 to securely retain said members together during use.

Where the slideable stud 92 and cooperating spring 86 are omitted however, it is obvious that the cooperating latch portions 16 and 18 of said members will be merely coupled after said portions have been brought into contact with each other, preferably in a true axial line and said members 12 and 14 have been manually tilted in any direction, the cooperating concave and convex surfaces 38 and 114 sliding over each other in any direction and the lip 120 registering in the annular space 122 formed between the convex lower edge 52 of the stud 44 and the concave guiding surface of the flange 32. Nevertheless, Fig. 2 illustrates how it would be impossible to separate the said members on a true axial pull on each member when tilted into this position as in use on a cuff.

It is obvious that I have provided a separable cuff button which will lock on mere relative tilted movement of the component male and female members thereof, which may be tilted in any direction, which can be put in in any way, which can be used on soft or stiff cuffs, which will readily conform to any angularity of the cuffs, which may be inserted in the dark, that I have provided locking means therefore to keep said members locked during normal use thereof, which locking means also operates to axially align said members to permit facile separation, that I have provided a separable cuff button which is impossible to separate in use having no projecting knobs or devices on the base to spoil the design, no projections or levers to tear the cuffs, no long protruding stems to hinder insertion and a device which may be manipulated without insertion of the fingers between the cuffs.

It is understood that my invention is not limited to the specific embodiment shown and that various deviations may be made therefrom without departing from the spirit and scope of the appended claims.

What I claim as new and desire to secure as Letters Patent is:—

1. A separable cuff button comprising two cooperating members each having a head, a shank and a base, the heads of said members comprising cooperating, complementary latch portions adapted to couple and to securely interlock said members at an angle to each other when said portions are brought into contact with each other, and said members are manually tilted.

2. A separable cuff button comprising two cooperating members each having a head, a shank and a base, the heads of said members comprising cooperating, complementary latch portions, adapted to couple and to

securely interlock said members at an angle to each other when said portions are brought into contact with each other, and said members are manually tilted, and means on said members to align said members to permit separation thereof. 70

3. A separable cuff button comprising two cooperating members each having a head, a shank and a base, the heads of said members comprising cooperating, complementary latch portions forming a universal joint adapted to couple and to securely interlock said members at an angle to each other when said portions are brought into contact with each other and said members are manually tilted in any direction. 75

4. A separable cuff button comprising two cooperating members each having a head, a shank and a base, the heads of said members comprising co-operating, complementary latch portions forming a universal joint adapted to couple and to securely interlock said members at an angle to each other when said portions are brought into contact with each other and said members are manually tilted in any direction, and means on said members to align said members to permit separation thereof. 85

5. A separable cuff button, comprising two cooperating male and female members each having a head, a shank and a base, the head of the male member comprising a cup shaped guiding flange projecting integrally arcuately outwardly and upwardly from said shank, the upper edge thereof forming a concave guiding surface and a stud member having a stem mounted centrally of said shank having a flat mushroom shaped head offset from said guiding flange having an annular ridge on the centre of the upper surface thereof, the head of the female member comprising a socket wall extending substantially spherically downwardly from the shank thereof to form a convex surface on the lower edge thereof to cooperate with the concave surface of the guiding flange of the male member, said wall terminating in a central circular hole of slightly greater diameter than the head of the stud of the male member to form an annular arcuate lip 100

adapted to register in a portion of the annular space formed between the guiding flange and head of the stud of the male member to retain said members together when relatively tilted and a stud member resiliently slidably mounted in the shank of the female member having an end projecting within the socket of the female member adapted to resiliently spring within said annular ridge on the head of the male member 105

two cooperating male and female members each having a head, a shank and a base, the head of the male member comprising a cup-shaped guiding flange projecting integrally 5 arcuately outwardly and upwardly from said shank, the upper edge thereof forming a concave guiding surface and a stud member having a stem mounted centrally of said shank having a flat mushroom shaped head 10 offset from said guiding flange, the head of the female member comprising a socket wall extending substantially spherically downwardly from the shank thereof to form a convex surface on the lower edge thereof to 15 cooperate with the concave surface of the guiding flange of the male member, said wall terminating in a central circular hole of slightly greater diameter than the head of the stud of the male member to form an 20 annular arcuate lip adapted to register in a portion of the annular space formed between the guiding flange and head of the stud of the male member to retain said members together when relatively tilted off center in use.

7. A separable cuff button, comprising two cooperating male and female members, each having a head, a shank and a base, the head of the male member comprising a cup-shaped guiding flange projecting integrally 30 arcuately outwardly and upwardly from said shank, the upper edge thereof forming a concave guiding surface and a stud member having a stem mounted centrally of said shank having a flat mushroom shaped head 35 offset from said guiding flange, the head of the female member comprising a socket wall extending substantially spherically downwardly from the shank thereof to form a convex surface on the lower edge thereof to 40 cooperate with the concave surface of the guiding flange of the male member, said wall terminating in a central circular hole of slightly greater diameter than the head of the stud of the male member to form an 45 annular arcuate lip adapted to register in a portion of the annular space formed between the guiding flange and head of the stud of the male member to retain said members together when relatively tilted and means on said members to relatively align said members to permit withdrawal of the head of the stud of the male member.

55 8. A separable fastener, comprising separable members each having a base at one end thereof and being provided at their other ends with complementary engaging surfaces, one of said surfaces being concave and 60 the other convex, the concave surface having a stud member projecting centrally therefrom having a flat head offset from said concave surface and the convex surface having a substantially spherical socket having 65 a central opening in the wall thereof, the

edge thereof thus terminating in an annular arcuate lip adapted to register in the space between said concave surface and offset stud head to retain said members together when relatively tilted.

70

9. A separable fastener, comprising separable members each having a base at one end thereof and being provided at their other ends with complementary engaging surfaces one of said surfaces being concave and the other convex, the concave surface having a stud member projecting centrally therefrom having a flat head having a central annular ridge on the upper surface thereof offset from said concave surface and the convex surface having a substantially spherical central socket opening in the wall thereof, the edge thereof thus terminating in an annular arcuate lip adapted to register in the space between said concave surface and offset stud head 80 to retain said members together when relatively tilted and a stud member resiliently slidably mounted in the shank of the female member having an end projecting within the socket of the female member adapted to resiliently spring within said annular ridge on the head of the stud of the male member to axially align said members on tilting thereof to permit withdrawal of the lip of the female member over the head of the stud of the male member.

90

10. A separable fastener, comprising separable members each having a base at one end thereof and being provided at their other ends with complementary engaging surfaces, one of said surfaces being concave and the other convex, the concave surface having a stud member projecting centrally therefrom having a flat head offset from said concave surface and the convex surface having a substantially spherical central socket opening in the wall thereof, the edge thereof thus terminating in an annular arcuate lip adapted to register in the space between said concave surface and offset stud head 100 to retain said members together when relatively tilted and means on said members to relatively align said members to permit withdrawal of the lip of the female member over the head of the stud of the male member.

105

11. A separable cuff button, comprising two cooperating male and female members each having a head, a shank and a base, the head of said male member comprising a cup-shaped guiding flange projecting integrally arcuately outwardly and upwardly from the shank thereof the upper portion thereof being bent back on itself over the lower layer thereof to form a strengthening 110 radially inwardly projecting flange terminating in a central hole, the upper surface thereof forming a concave guiding surface and a stud member having a stem mounted centrally of said shank having a mushroom shaped head having a flat upper 115

115

120

125

130

- surface provided with a central annular ridge and a convex lower surface offset from said concave guiding surface, the shank of the female member terminating in a radially 5 spread out flange, the lower portion thereof being bent back on itself over the upper layer to form a strengthening radially inwardly projecting flange terminating in a central hole, an annular washer provided 10 with a central hole resting on the lower surface of said flange, a dome shaped cap secured over said washer to said radial shank flange, the lower surface of the wall thereof forming a convex surface to cooperate 15 with the concave guiding surface of the male member and the lower portion of said wall terminating in a central circular hole of slightly greater diameter than the head of the stud of the male member to form a 20 substantially semi-spherical socket having an annular arcuate lip adapted to register in a portion of the annular space formed between the guiding flange and head of the stud of the male member to retain said members together when relatively tilted, a washer mounted 25 in the base of the female member having a central hole, a spiral spring having the base thereof resting within said hole and a stud member slidably mounted in the shank thereof having the base thereof resting on the top of the spiral spring and the head thereof projecting into said socket having a shoulder to abut the edges of the hole in said washer to limit its downward movement and a pointed end adapted to resiliently spring 30 within said annular ridge on the head of the stud of the male member to axially align said members on relative tilting thereof to permit withdrawal of the lip of the female member over the head of the stud of the male member. 35
12. A separable cuff button, comprising two cooperating male and female members, each having a head, a shank and a base, the head of said male member comprising a cup-shaped guiding flange projecting integrally arcuately outwardly and upwardly from the shank thereof, the upper surface thereof forming a concave guiding surface and a stud member having a stem mounted centrally of said shank having a mushroom shaped head having a flat upper surface provided with a central annular ridge and a convex lower surface offset from said concave guiding surface. 40
13. A shank for use in separable cuff buttons having at the outer end thereof an integral outer layer bent over on the inner layer to form a double strengthening thickness of metal. 45
14. A shank for use in separable cuff buttons having at the outer end thereof a flange comprising an integral outer layer bent over on the inner layer to form a double strengthening thickness of metal. 50
15. A cuff button, having a male member comprising a head, a shank and a base, the head thereof comprising a cup shaped guiding flange projecting integrally arcuately outwardly and upwardly from the shank, the upper portion thereof being bent back on itself over the lower layer thereof to form a strengthening radially inwardly projecting flange terminating in a central hole, the upper surface thereof forming a concave guiding surface and a stud member having a stem mounted centrally of said shank having a mushroom shaped head having a flat upper surface provided with a central annular ridge and a convex lower surface offset from said concave guiding surface. 55
16. A cuff button, having a male member comprising a head, a shank and a base the head thereof comprising a cup-shaped guiding flange projecting integrally arcuately outwardly and upwardly from the shank, the upper surface thereof forming a concave guiding surface and a stud member having a stem mounted centrally of said shank having a mushroom-shaped head having a flat upper surface provided with a central annular ridge and a convex lower surface offset from said concave guiding surface. 60
17. A cuff button, having a male member 65

comprising a head, a shank and a base, the head thereof comprising a cup shaped guiding flange projecting integrally arcuately outwardly and upwardly from the shank, 5 the upper surface thereof forming a concave guiding surface and a stud member having a stem mounted centrally of said shank having a mushroom shaped head having a convex lower surface offset from said 10 concave guiding surface.

18. A cuff button, having a member comprising a base, a shank and a flange projecting concavely upwardly from said shank and a stud member projecting therefrom 15 having a flattened head offset from said flange.

19. A cuff button, having a female member comprising a base, a head and a shank, the shank thereof terminating in a radially 20 spread out flange, the lower portion thereof being bent back on itself over the upper layer to form a strengthening radially inwardly projecting flange terminating in a central hole, an annular washer provided 25 with a central hole resting on the lower surface of said flange, a dome shaped cap secured over said washer to said radial shank flange, the lower surface of the wall thereof forming a convex surface, the lower portion 30 of said wall terminating in a central circular hole, a washer centrally mounted in the base thereof having a central hole, a spiral spring having the base thereof resting within said hole and a stud member 35 slidably mounted in the shank thereof having the base thereof resting on the top of the spiral spring and the head thereof projecting into said socket having a shoulder adapted to abut the edge of the hole in said 40 washer to limit its downward movement and a pointed head projecting within said socket.

20. A cuff button, having a female member comprising a base, a head and a shank, the shank thereof terminating in a radially 45 spread out flange, an annular washer provided with a central hole resting on the lower surface of said flange, a dome shaped cap secured over said washer to said radial shank flange the lower surface of the wall 50 thereof forming a convex surface the lower portion of said wall terminating in a central circular hole, a washer centrally mounted in the base thereof having a central hole, a spiral spring having the base thereof resting within said hole and a stud member 55 slidably mounted in the shank thereof having the base thereof resting on the top of the spiral spring and the head thereof projecting into said socket having a shoulder adapted to abut the edge of the hole in said 60 washer to limit its downward movement and a pointed head projecting within said socket.

21. A cuff button, having a female member comprising a base, a head and a shank, 65 the head thereof comprising a socket wall

extending substantially spherically downwardly from the shank thereof to form a convex surface on the lower edge thereof, said wall terminating in a central circular hole to form an annular arcuate lip, and a 70 stud member resiliently mounted in the shank thereof having an end projecting within said socket.

22. A cuff button, having a female member comprising a base, a shank and a head, the 75 head thereof comprising a socket wall extending substantially spherically downwardly from the shank thereof to form a convex surface on the lower edge of said wall, terminating in a central circular hole to form 80 an annular arcuate lip.

23. A separable fastener comprising two members having cooperating complementary latch portions adapted to couple said members after said portions are brought into 85 contact with each other and said members are manually tilted, and means on said members to axially align said members to permit separation thereof.

24. A separable fastener comprising two members having cooperating complementary latch portions forming an universal joint adapted to couple said members after said portions are brought into contact with each other and said members are manually tilted 95 in any direction.

25. A separable fastener comprising two members having cooperating complementary latch portions forming an universal joint adapted to couple said members after said 100 portions are brought into contact with each other and said members are manually tilted in any direction and means on said members to axially align said members to permit separation thereof.

26. A separable fastener comprising two members having cooperating complementary latch portions adapted to couple and to securely interlock said members at an angle to each other after said portions are brought 110 into contact with each other and said members are manually tilted, and means on said members to axially align said members to permit separation thereof.

27. A separable fastener comprising two members having cooperating complementary latch portions adapted to couple and to securely interlock said members at an angle to each other after said portions are brought 115 into contact with each other and said members are manually tilted.

28. A separable fastener comprising two members having cooperating complementary latch portions adapted to couple and to securely interlock said members at an angle to each other after said portions are brought 125 axially into contact with each other and said members are manually tilted.

29. A separable fastener comprising two 130 members having cooperating complementary

latch portions forming an universal joint adapted to couple and to securely interlock said members at an angle to each other after said portions are brought into contact with each other and said members are manually tilted in any direction.

30. A separable fastener comprising two members having cooperating complementary latch portions forming an universal joint adapted to couple and to securely interlock said members at an angle to each other after said portions are brought into contact with each other and said members are manually tilted in any direction and means on said members to axially align said members to permit separation thereof.

31. A separable fastener comprising two members having cooperating complementary latch portions adapted to couple said mem-

bers after said portions are brought axially into contact with each other and said members are manually tilted, and means on said members to axially align said members to permit separation thereof.

32. A cuff link comprising in combination separable cuff buttons, one of said buttons comprising a base, a stem, and a hollow coupling member formed with an aperture, and the other button comprising a base, a stem, and a co-operating coupling member adapted to pass through said aperture, and means for yieldably holding said last-amended coupling member, when engaged within said hollow coupling member, out of register with said aperture.

35 In testimony whereof I affix my signature.

FRANS EDWARD FORSELL.
